UNITED STATES PATENT OFFICE.

BYRON SWEET, OF POPLAR GROVE, ILLINOIS.

GRINDING-MACHINE.

1,173,225.

Specification of Letters Patent. Patented Feb. 29, 1916.

Application filed October 23, 1915. Serial No. 57,429.

To all whom it may concern:

Be it known that I, BYRON SWEET, a citizen of the United States, residing at Poplar Grove, in the county of Boone and State of Illinois, have invented certain new and useful Improvements in Grinding-Machines, of which the following is a specification.

This invention relates in general to grinding machines and has more particular reference to those especially adapted for sharpening mower and reaper cutting knives or sickles.

Grinding machines of this character have been in most instances so constructed that the grinding wheel when in operation is automatically moved back and forth over the surfaces being ground. Generally, in such machines a cone-faced grinding wheel is employed, adapted to simultaneously sharpen the edges of two adjoining knife sections. Usage of a cutter bar develops irregularities in the cutting edge of its sections, and repeated sharpening with a cone-faced grinding wheel results in a somewhat concave cutting edge. When a grinding machine of this type and in which the grinding wheel is automatically oscillated in a fixed path is employed for sharpening a cutter bar having such irregularities in the cutting edges, these edges are not properly sharpened, since the control of the wheel is not such as will permit proper adaptation to the peculiarities of each cutting edge.

The primary object of my invention is to provide a grinding machine for sharpening mower and reaper knives in which the grinding wheel shall be under immediate, direct manual control of the operator, so that he may position and apply the wheel to the knife sections in the proper relation to obtain perfect sharpening of the edges regardless of irregularities therein.

My invention also contemplates the provision of a grinding machine which, while adapted to sharpen but one edge of a section at one time, may be applied to the edge of the next adjoining section without changing or adjusting the position of the sickle, by simply oscillating the grinding wheel so as to dispose its grinding face at the angle of the said adjacent edge. This adjustment may be attained instantaneously, since the grinding wheel is under direct manual control of the operator.

Another object of my invention is to provide a grinding machine of the character de-

scribed of simple and improved construction, which may be cheaply manufactured and easily operated.

The foregoing and other objects and advantages of my invention will be more readily apparent as the same becomes better understood by reference to the following description when considered in connection with the accompanying drawings, wherein,—

Figure 1 is a side elevation of my improved grinding machine, showing the same in normal inoperative position; Fig. 2 is a plan view thereof; Fig. 3 is an enlarged vertical sectional view through the machine taken on the line 3—3 of Fig. 2, showing one position of the grinding wheel when in operation; Fig. 4 is a vertical sectional view taken on the line 4—4 of Fig. 3; Fig. 5 is a plan view of a portion of a sickle shown as disposed directly below the grinding wheel; Fig. 6 is a cross sectional view through the grinding head taken on the line 6—6 of Fig. 1; and Fig. 7 is a detail view in perspective of a bearing block employed in the mounting of the grinding wheel.

Referring to the drawings, it will be observed that a frame suitable for supporting the several working elements employed in my grinding machine, comprises legs 8, spaced apart by upper and lower side bars 9 and 11 respectively, and by cross bars 12, 13, 14, and 15. The cross bar 15, the ends of which extend beyond the side of the frame constitutes with the brackets 16 secured thereto, a work support adapted to receive a cutting knife or sickle such as is employed in mowers and reapers. The sections of the sickle rest upon the top face of the bar 15 and the rib or backing thereof is engaged by the bracket 16 and held against lateral displacement while permitting the sickle to be freely adjusted lengthwise thereon. The work supporting bar 15 is recessed at 10 so as to provide clearance for the grinding wheel adapted to be employed in sharpening a knife positioned on the work support.

Means for supporting and guiding the grinding wheel 17 into and out of operative relation with the rest 15 comprises a pivoted frame and a holder designated in general by reference characters 18 and 19 respectively. The frame 18 triangular in shape as shown in Fig. 2, is pivoted at one end on the ends of a shaft 21 mounted fixedly on upright posts 22 and 23 which are interposed between and secured to the cross

bars 13 and 14. These posts are formed with a slot extending to the shaft aperture so that a bolt 25 passed through the split sections of the post may be tightened to 5 clamp the post to the shaft 21. The post 23 extends considerably higher than the post 22 so as to provide a point of attachment for a coiled spring 26 which is connected to the outer end of the supporting frame 18 for 10 constantly urging the said frame upwardly. A grooved pulley 27 and a pulley 28 of smaller diameter rigidly secured thereto are rotatably mounted on the shaft 21 between the posts 22 and 23. The pivoted support 15 18 is provided with an extensible end upon which the grinding wheel 17 is journaled. This extensible end is so mounted as to turn on an axis intersecting that of the grinding wheel at right angles so that 20 the grinding wheel may not only be moved toward and away from the support 18 but oscillated laterally with respect thereto. In the present instance, I have illustrated this end structure in the 25 form of a pipe section 29 slidably and rotatably mounted in spaced cross pieces 31 and 32 of the support 18, the outer end of the pipe section being split and shaped to provide a forked end between the arms 33 of 30 which is mounted the grinding wheel. Referring to Fig. 6, it will be noted that the grinding wheel 17 of a flat faced type and a grooved pulley 30 are clamped fixedly together on an arbor or spindle 34 by nuts 35, 35 the reduced ends 36 of which are journaled in blocks 37. These blocks, preferably of 40 wood, are shaped on their outer sides with ribs 38 fitting in the channels of the pipe section arms 33, the blocks being fixedly secured thereto by bolts 39. To facilitate assembling the grinding wheel head and obtain simplicity in construction, the bearing blocks are formed with oblique slots 41 leading to the bearing aperture there- 45 through whereby the ends 36 of the arbor 34 may be quickly and easily positioned in the blocks after the grinding wheel and pulley have been secured to the arbor, rods 42 passing lengthwise through the blocks being em- 50 ployed to hold the arbor against withdrawal from the slots. These bolts secured in position by nuts at the ends of the blocks are extended forwardly so as to afford a sup- 55 port for a handle 43 which is bolted to the rods as is shown clearly in Fig. 3. Driving connection between the pulleys 27 and 30 is established by means of a coiled wire spring belt 44.

From the foregoing, it will be apparent 60 that without disturbing the driving connection between the grinding wheel and drive pulley an operator grasping the handle 43 may raise and lower the grinding wheel in an arcuate path about the pivot axis of the 65 support 18, draw the wheel backwardly and

forwardly by reason of the slidable mounting of the forked holder 19, and oscillate the wheel laterally on the longitudinal axis of the said holder.

Foot-operated means are provided for 70 moving the grinding wheel back and forth over the work support so that an operator seated in front of the machine may control the angle and depth of grinding by hand and effect the back and forth feeding move- 75 ment by foot operation. The foot-operated means comprises a lever 45 pivoted intermediate its ends at 46 on a block 47 centrally fixed to the cross bar 12, the upper end of the lever being formed to provide a yoke 48 80 passing over the rod 29 and the lower end being provided with laterally projecting foot rests 49. By swinging the lower end of the lever 45 backwardly its upper yoked end 48 will be swung forwardly into engage- 85 ment with a laterally projecting pin 51 on the rod 29 so as to move the grinding wheel head forwardly or outwardly on the frame 18, such movement being against the resistance of the spring belt 44. A stop 52 on 90 the inner end of the rod 29 limits, by abutting against cross piece 32, the outward movement of the grinding wheel head. When the operator releases his hold on the 95 grinding wheel head in the position shown in Fig. 3, the spring 26 will raise the wheel supporting frame 18 to normal inoperative position shown in Fig. 1, determined by abutment of the rod 29 against the closed outer end of the yoke 48.

In operating the grinding machine, the pulley 28 being driven by a belt from a suitable source of power, a knife is positioned on the support 15 so that two adjoining knife sections thereof are disposed over the 105 clearance recess 10, in the manner shown in Fig. 5. An operator seated in front of the machine with his feet on the rests 49 and grasping the handle 43 is then ready to commence the sharpening operation. The grinding wheel head will be lowered by hand and advanced toward the cutter bar by pushing backwardly on the foot rest until the grinding wheel with its axis of rotation horizontally disposed, is positioned centrally intermediate the teeth A and B. To sharpen 110 the edge A' the operator cant the grinding wheel to the right by hand until the face thereof assumes an angle corresponding to the bevel of the cutting edge. The foot lever is then operated to advance the cutting wheel, the path of the wheel, the angle 115 of its face and the depth of grinding being determined and controlled by hand. In sharpening the face A', the cutting face of 120 the wheel having been properly angled will travel in the path indicated by dotted lines 52, Fig. 5, it being apparent that during the advancing of the wheel along the cutting edge, the operator may control to a 125 130

nicety the depth and angle of grinding, and that should the cutting edge contain irregularities or notches, these may be properly ground by correct manipulation of the 5 grinding wheel through the handle 43. To grind the edge B' of the adjoining knife, the grinding wheel is canted in the opposite direction so that the angle of its face corresponds to the bevel of the cutting edge of 10 this knife, and since the wheel will not quite contact the said cutting edge after being canted, the sickle should be moved lengthwise to the left until in proper relation to the wheel, which is then worked back and 15 forth in the manner previously described until this edge has been sufficiently ground. Should the operator, after having finished grinding an edge of a knife section, or at any time, releases his grasp on the handle 20 43, the grinding head will be instantly raised to inoperative position by the spring 26 and held in such position by the yoke 48. As will be apparent, to sharpen the remaining 25 sections of the knife, the same may be adjusted lengthwise to position the next adjacent cutting edges over the clearance recess 10 and the grinding operations above described repeated.

With my improved grinding machine, a 30 sickle may be very satisfactorily sharpened in a short period of time and with each cutting edge properly ground throughout its entire length. It will be noted that the important and delicate operations of guiding 35 the grinding wheel at the proper angle and determining the depth of grinding is controlled by hand and that the operation of feeding the grinding wheel back and forth is effected by foot control. 40 Thus, the more delicate hand control is relieved of that operation, the feeding, which requires force rather than precision in guiding the grinding wheel. It will also be noted that the particular construction of the 45 several parts constituting my improvements are such that, if necessary, they may be replaced very easily, since the construction is exceedingly simple and requires practically no machine work in making the several 50 parts.

From the foregoing it is believed that my invention and the principles of operation involved will be readily understood, and it should be apparent that various changes in 55 details of construction might be resorted to without departing from the invention or sacrificing any of its material advantages.

I claim:

1. In a grinding machine, the combination 60 of a drive pulley, a swinging frame coaxially mounted with the drive pulley, a grinding wheel, means slidably mounted upon and movable longitudinally of said frame and supporting the grinding wheel 65 adjacent to the outer end of the frame, and

a contractile spring belt connecting the drive pulley and grinding wheel.

2. In a grinding machine, the combination of a supporting frame provided at its front end with a work support, a swinging frame 70 pivoted on a horizontal axis to the rear portion of the supporting frame and extending forwardly toward said work support, a grinding wheel, means so slidably supporting the grinding wheel on the pivoted frame 75 that the grinding wheel may be reciprocably moved longitudinally thereon so as to be capable of back and forth feed movement relative to the work support, hand operable means in connection with the grinding 80 wheel whereby the same may be swung by hand on the pivot axis of said swinging frame toward and away from the work support, means for rotating the grinding wheel, and means for reciprocating said 85 grinding wheel supporting means on said swinging frame.

3. In a grinding machine, the combination of means for supporting a sickle, a grinding wheel, a frame pivoted at one end and supporting the grinding wheel at its outer end 90 over the sickle and so that the grinding wheel may be oscillated laterally and moved back and forth over the work support relatively to the pivot axis of said supporting 95 frame and swung toward and away from said support on the said pivot axis as a fulcrum, a pulley concentric with the pivot axis of said supporting frame, and a contractile spring belt driving connection between the grinding wheel and said pulley whereby the grinding wheel will be constantly urged toward the said pivot axis and capable of said lateral oscillation and back 100 and forth movement.

4. In a grinding machine, the combination of a work support, a grinding wheel, a driving pulley mounted on a relatively fixed axis, a contractile spring belt connection between the pulley and the grinding wheel, 110 means supporting the grinding wheel in such manner that it may be moved back and forth between and with respect to its driving pulley and the work support and oscillated on an axis substantially intersecting that of 115 the grinding wheel at right angles, said spring belt constantly urging the grinding wheel toward said driving pulley and handle means connected with the grinding wheel whereby an operator may by direct manual 120 control of the grinding wheel position it at an angle with respect to work on the work support and move the wheel back and forth in the grinding operation, in which latter movement the grinding wheel is moved 125 away from the said driving pulley against the tension of said spring belt.

5. In a grinding machine, the combination of a work support and a driving pulley spaced apart in fixed relation, a grinding 130

wheel, a holder therefor carrying the grinding wheel normally disposed intermediate the work support and pulley, and a contractile spring belt connection between the 5 pulley and grinding wheel for rotating the latter, said grinding wheel holder being so constructed that the grinding wheel may be moved back and forth over the work support and oscillated on an axis substantially 10 intersecting that of the wheel at right angles, the said holder being movable over the work support away from the driving pulley against the tension of said spring and consequently, being constantly urged toward 15 the driving wheel by said spring.

6. In a grinding machine, the combination of a work support and a driving pulley mounted in fixed spaced relation, a frame pivoted coaxially with the driving pulley 20 and extending therefrom toward the work support, a grinding wheel, means movably securing the grinding wheel to said frame so that the grinding wheel may be moved longitudinally of the said frame whereby 25 the proximity of the grinding wheel to the work support may be varied by swinging said frame on its pivot and the grinding wheel may be moved longitudinally upon and with respect to said frame so as to be 30 moved back and forth relatively to the work support, and a contractile spring belt connecting the driving pulley and grinding wheel whereby the latter is driven and is capable of said back and forth movement 35 and whereby also the spring constantly urges the grinding wheel toward the driving pulley.

7. A grinding machine, comprising a frame, a work support and a grinding wheel 40 support mounted thereon spaced apart horizontally in fixed relation, the grinding wheel support being pivoted on a horizontal axis at its end farthest from the work support, a driving pulley co-axial with the 45 pivot axis of the wheel support, a grinding wheel, a holder therefor so mounted on the wheel support as to be movable lengthwise

thereof toward and away from its pivoted end, a spring belt connection between the grinding wheel and drive pulley, and a 50 lever pivoted on the frame beneath the wheel support, connected at its upper end with the wheel holder, and being operable so as to move the wheel holder lengthwise to move the grinding wheel back and forth 55 over work positioned on the work holder.

8. A grinding machine, comprising a frame, a horizontally disposed support pivoted at one end on the frame on a horizontal axis, a grinding wheel, a holder upon 60 which the grinding wheel is journaled on a horizontally disposed axis, the holder being so slidably and rotatably mounted on the outer end of said support that it may be slid horizontally lengthwise of the support 65 and turned on a horizontal axis intersecting the wheel, a pulley fixedly connected with the grinding wheel, a pulley mounted on the pivot axis of said support, a spring belt connection between the said pulley constantly urging the wheel holder to an innermost position on the support, a work support mounted on the frame beneath and at the outer end of the wheel holder, means 70 constantly urging the outer end of the wheel support upwardly, and controlling means operable to move the grinding wheel into grinding relation with work on the work support and to move the wheel backwardly and forwardly over said work and to turn 80 it laterally on its holder axis.

9. In a grinding machine, the combination with a work support and a drive pulley spaced apart in fixed relation, of a swinging frame coaxially mounted with said drive 85 pulley and extending therefrom toward the work support, a grinding wheel, means supporting the grinding wheel on the outer end of said frame and being movable longitudinally upon and with respect thereto, and a 90 contractile spring belt connecting the drive pulley and grinding wheel.

BYRON SWEET.
